UNITED STATES PATENT OFFICE

REINHARD E. BARTELS, OF LYNN, MASSACHUSETTS; IDA M. BARTELS AND R. BUR-
LEIGH BARTELS EXECUTORS OF SAID REINHARD E. BARTELS, DECEASED

SHANK STIFFENER

Original application filed June 30, 1922, Serial No. 571,859. Divided and this application filed March 10, 1926. Serial No. 93,598.

This application is a division of my co-pending application Serial No. 571,859, filed June 30, 1922, upon which Letters Patent No. 1,580,278 were granted April 13, 1926. 5 The invention relates to shank stiffeners more particularly intended for welt shoes, though applicable to other types of shoes, and provides a construction by which great stiffness and strength may be provided with 10 comparatively little weight. For this purpose the stiffener is substantially tubular in cross section between its ends where the stress of use is greatest, this tubular construction being preferably formed by two 15 stiffener members or blanks fixed face to face, one of these blanks being curved laterally.

Means are also provided for interlocking the stiffener members the method of manufacture insuring against play between the members when in use.

For a more complete understanding of the invention, together with further objects and advantageous details and combinations of 25 parts, reference may be had to the accompanying drawings, in which

Figure 1 is a perspective of the longer stiffener member as prepared for attachment with the shorter member.

30 Figure 2 is a plan of the shorter member prepared for assembly with the longer member.

Figure 3 is a longitudinal section on line 3—3 of Figure 2.

35 Figure 4 is a side elevation of the members assembled ready for incorporation in the shoe.

Figure 5 is a cross section on line 5—5 of Figure 4.

40 Figure 6 is a fragmentary inverted plan of a welt innersole showing the stiffener in position.

Figure 7 is a section substantially on line 7—7 of Figure 6.

45 One of the members forming the shank stiffener comprises a stiff substantially rectangular blank 1, preferably of metal, which is shown detached in Figure 1. The blank adjacent each end is provided with one or 50 more slots 2, as shown a pair of such slots

being provided adjacent each end of the blank. Outwardly of these slots the blank is punched out at 3 to form prongs 4 by which the stiffener may be fixed in position on the shoe. The other stiffener member is shorter than the blank 1 and is shown detached at 5 in Figure 2. This member, also preferably metallic, is curved laterally between its ends to form an arch-shaped portion 6 and adjacent its ends it has struck therefrom at 7 prongs or tines 8 spaced to correspond with the slots 2. These two stiffener members are then assembled face to face with the prongs 8 extending through the slots 2 and folded against the remote face of the member 1 as shown in Figure 4. The combined stiffener is then molded longitudinally to the shape shown in Figure 4, the longer member 1 being on the convexed side of the stiffener. This curving of the stiffener causes the prongs 8 to be sprung or jammed against a side of the slots 2 so that they are thus firmly and tightly interlocked with the member 1 and all looseness or play between the members is eliminated. The arch 6 forms with the stiffener member 1 a substantially tubular stiffener, one face being flat and the other rounded. The molding of the strips longitudinally after they have been secured together results in a springing of the strips which imposes longitudinal stresses upon them, tension on the longer strip and compression on the shorter. This forms an exceedingly stiff construction between the ends of the stiffener where strength is of most importance and it is flat at its ends where it is attached to the innersole.

In Figures 6 and 7 the stiffener so formed of the two members 1 and 5 is shown as attached to the innersole of a welt shoe between the stitch-receiving ribs 10, the prongs 4 extending into the innersole and clinched therein to fasten the stiffener in position.

Having thus described an embodiment of this invention, it should be evident that various changes and modifications might be made therein without departing from its spirit or scope as defined by the appended claims.

I claim:

1. A shank stiffener comprising superposed metallic stiffener strips molded to the desired longitudinal curvature, one of said strips being shorter than the other and having tines engaging in slots in the other to fasten them together, said shorter strip being molded to a lateral curvature.
2. A shank stiffener comprising superposed stiffener strips molded to the desired longitudinal curvature, one of said strips being shorter than the other and having tines engaging in slots in the other to fasten them together, said shorter strip being molded to a lateral curvature, and tines on said longer member beyond the ends of said shorter member for fixing said stiffener in a shoe.
3. A shank stiffener comprising superposed metallic stiffener strips molded to the desired longitudinal curvature, one of said strips having slots therethrough, the other said strip having tines extending through said slots, said strips being respectively under tension and compression whereby the tines are tightly sprung against a side of their respective slots.
4. A shank stiffener comprising superposed metallic stiffener strips molded to the desired longitudinal curvature, one strip having slots therethrough, the other strip having tines projecting through said slots and tightly and permanently jammed against one side thereof.
5. A shank stiffener comprising superposed metallic stiffener strips molded to the desired longitudinal curvature, one strip having slots therethrough, and means for securing said strips together comprising tines extending through said slots and clinched, each tine being tightly and permanently jammed against a side of its slot.
6. A shank stiffener comprising superposed metallic stiffener strips molded to the desired longitudinal curvature, means integral with one of said strips and engaging the other strip to positively and permanently lock said strips against relative motion in any direction.
7. A shank stiffener comprising superposed metallic stiffener strips, one of said strips having apertures therethrough, and means for securing said strips together, said means comprising elements passing through said apertures and tightly jammed against one side thereof.

In testimony whereof I have affixed my signature.

REINHARD E. BARTELS.
